CLAIM

The ornamental design for a shoe as shown and described.

DESCRIPTION

FIG. 1 is a front perspective view of a shoe, showing my new design;
FIG. 2 is a rear perspective view thereof;
FIG. 3 is a right side view thereof;

FIG. 4 is a front view thereof;

FIG. 5 is a rear view thereof; and,

FIG. 6 is a top view thereof.

The dot-dash broken line represents a boundary of the claimed design and forms no part of the claimed design. The broken lines depicting the remainder of the shoe show features that form no part of the claimed design.
